UNITED STATES PATENT OFFICE.

GORHAM A. TAYLOR, OF DULUTH, MINNESOTA.

CABLE-EQUALIZER.

1,399,326.

Specification of Letters Patent.

Patented Dec. 6, 1921.

Application filed January 17, 1921. Serial No. 437,781.

To all whom it may concern:

Be it known that I, GORHAM A. TAYLOR, a citizen of the United States, residing at Duluth, in the county of St. Louis and State of Minnesota, have invented certain new and useful Improvements in Cable-Equalizers, of which the following is a specification, reference being had therein to the accompanying drawing.

10 This invention relates to draft equalizing devices and has special reference to such a device in connection with two parallel lines in which the pulling stress is in the same direction, such as are employed on what is known as a twin cable dipper dredge, used in deepening harbors or the like, and, while I have illustrated the device as used in connection with this particular art, it is evident that the same may be employed 15 where equalization of the pulling stress upon lines used for other purposes is desired.

The ordinary dredge, which is known as a twin cable dredge, that is one provided with a double cable leading forwardly from 20 the pulling drum and controlling the dipper of the dredge, has in reality but a single cable for this purpose, which extends forwardly from one side of the winding drum outwardly along the boom and through 25 what is known as the padlock or padlock sheave directly connected with the bail of the dipper of the dredge and back again, along side of the other portion of the line, to the other side of the differential pulling 30 drum; thus, when the drum is wound or unwound, the two sides of the cable operate simultaneously in like directions. While such dredges are known as "twin cable," they have, as before stated, but a single 35 cable which operates the dipper, and, in the event of this cable being broken at any point, the entire cable becomes a loss unless it may be successfully spliced, which is not considered practical.

40 45 The equalizing device, in such a combination, is the padlock sheave above referred to about which the line passes, and is free to alternately reciprocate as desired.

Within the peculiar construction of the 50 sheave and the device directly coöperative therewith resides my present invention, the principal object of which is to provide simple means whereby the use of two separate pulling lines may be employed, so that 55 in the event of one becoming broken or in

any way inoperative, it will not directly affect the other, or prevent its functioning.

Another object is to provide means whereby the wear, incident to the operation of such an equalizing device, is reduced to a minimum.

Still other objects and advantages of the invention will appear in the further description thereof.

In the accompanying drawing forming 65 part of this application and in which like reference characters indicate like parts:

Figure 1 is a side elevation of the equalizing padlock or sheave block, it being partly broken away to show in full lines the relative position of the chain which is reeved 70 within the block;

Fig. 2 is an edge elevation of the block with the chain removed therefrom; and

Fig. 3 is a reduced diagrammatic plan 75 view of a marine twin cable, dipper dredge.

The padlock or block comprises two spaced vertically elongated preferably octagonally shaped side members 1 and 2, intermediate of which the circumferentially 80 grooved sheave 3 is pivotally mounted upon the pin 4. Intermediate of the upper opposed corners of the side members 1 and 2 of the block are securely fixed the arcuately shaped chafing shoes 5, they being held in 85 position by the suitable through bolts 6. These shoes each have a groove 7 formed in their opposed arcuate faces, said grooves being similar in depth and size to the groove 8 in the sheave 3 and a short piece of chain 9 is reeved about the sheave 3 and brought 90 up upon both sides thereof intermediate of the shoes 5 and against which it bears.

The uppermost links 10 of the chain 9 are elongated and preferably larger at their 95 upper ends than at their lower ends, to provide for ample wearing surface upon the transverse holding pins 11, and I prefer to flatten the wearing face of the upper portion of the links 10 which bear downwardly 100 upon the pin 11 so that the link has a full bearing face thereupon. The pins 11 extend through the jaws 12 of the open jawed cable socket 13 intermediate of which the links 10 are carried and form a secure 105 pivotal contact with said sockets. The twin cables are illustrated at 14 and 15, they being, as before stated, properly termed "twin cables" for they are alike in all respects and extend upwardly and rearwardly along the 110

boom 16 of the dredge 17 to the pulling drum 18 thereupon; the dipper of the dredge being shown at 19 and the bail thereof at 20, to which the equalizer or padlock block 5 is attached in the usual manner.

In Fig. 3 of the drawing the equalizing block is illustrated at 21.

One of the principal features of this invention is the extension of the pins 11 sufficiently far beyond the spaced jaws of the sockets to prevent the chain being pulled downwardly through the padlock by said extending ends of the pin riding upon the upper edges of the sides 1 and 2 of the equalizing block in the event of one of the cables breaking and the normal distance of the pins above the upper edge of the block being ample to provide for any equalizing action of the chain.

20 A semi-circularly shaped channel bar 22 is securely fixed intermediate of the side members 1 and 2 of the block below the sheave 3 and concentric therewith to act as a guide for the chain 9 and to prevent its possible jumping out of the sheave 3, but which guide is not considered new in this application, as the same is known to be old.

From the foregoing it is evident that I have devised a simple equalizing block for 30 two pulling cables which will provide ample equalization of any differential strain which may occur upon the lines, and that, in the

event of either line breaking, the opposite line will be automatically prevented from disengagement with the block, the advantages of which are obvious.

Having thus described my invention, what I claim and desire to secure by Letters Patent, is:

1. The combination with the termini of two pulling lines having a sheave block adjacent said termini, of a chain reeved about the sheave within the block and attached to the ends of the lines, and means co-operatively connected with said attachment to prevent either end of the chain being pulled through the block.

2. The combination with a twin cable dredge of the character described having an equalizing padlock co-operatively connecting the dipper of the dredge with the twin cables and a reeved chain within the padlock uniting the ends of the twin cables, of means co-operatively engaged with the padlock to prevent one of the cables from being disengaged from the padlock in the event of the other cable being broken.

In testimony whereof I hereunto affix my signature in the presence of two witnesses.

GORHAM A. TAYLOR.
